UNITED STATES PATENT OFFICE.

JAMES HAMMOND, OF MOUNDSVILLE, WEST VIRGINIA, ASSIGNOR OF ONE-THIRD TO
JAKE WILLIAMS, OF MOUNDSVILLE, WEST VIRGINIA.

ENVELOP-MOISTENING DEVICE.

1,027,204.

Specification of Letters Patent.

Patented May 21, 1912.

Application filed October 27, 1911. Serial No. 657,092.

To all whom it may concern:

Be it known that I, JAMES HAMMOND, a citizen of the United States of America, residing at Moundsville, in the county of Marion and State of West Virginia, have invented certain new and useful Improvements in Envelop-Moistening Devices, of which the following is a specification, reference being had therein to the accompanying drawing.

This invention relates to an envelop moistening device, and the primary object of my invention is the provision of novel means for moistening the flap of an envelop without resorting to the use of daubing devices or the licking of an envelop flap.

Another object of this invention is to provide an envelop moistening device with a reservoir for supplying a liquid to the pads of the device.

With the above and other objects in view, the invention resides in the novel construction, combination and arrangement of parts to be hereinafter specifically described and then claimed.

Reference will now be had to the drawing, wherein:

Figure 1 is a perspective view of the device, and Fig. 2 is a cross sectional view of the same.

A device in accordance with this invention comprises a structure having a base plate 1, end walls 2, a rear wall 3, a front wall 4 and a platform 5. The base plate 1 projects beyond the end walls 2 and the lower edges of said walls beyond the front wall 4, with the platform 5 in a plane parallel with the base plate 1. Formed integral with the end walls 2 and converging to a point centrally of the device are reservoir walls 6, these walls being formed integral with a top plate 7 which is connected to the rear wall 3 and also to the end walls 2. The walls 6 are connected with the platform 5, the latter being also connected to the rear wall 3. The platform 5, walls 2, 3 and 6 and the top plate 7 form a reservoir 8 for a liquid, as water or mucilage. Access is had to the reservoir 8 for filling purposes through the medium of an opening 9 in the rear wall 3, said opening being normally closed by a screw plug 10.

The platform 5 is provided with an angle recess 11 for an angle pad 12 made of felt or other absorbent material. This angle

pad permits of the flap of an envelop being placed thereon for moistening purposes, the shape of the pad accommodating the edges of various sizes of envelop flaps.

The walls 6 are provided with angularly disposed ports 13 with the lower ends of said ports terminating in proximity to the pad 12. The upper ends of the ports terminate in guides 14 within the reservoir 8. Arranged in said guides and adapted to normally close the ports 13 are the lower angle ends 15 of valve stems 16. These stems extend upwardly through tapering openings 17 and through cylindrical sockets 18 carried by the top plate 7. The sockets 18 are provided with caps 19 through which said valve stems extend, said stems having buttons or heads 20 to facilitate elevating said stems. The stems are normally retained in a lowered position by coiled retractile springs 21 arranged within the sockets 18, the lower ends of said springs being connected, as at 22 to the stems 16, while the upper ends of said springs engage the inner sides of the caps 19. By elevating the stems 16, a portion of the liquid can escape through the ports 13 on to the pad 12 and in this manner the pad can be always maintained moist for instant use.

Movably suspended above the pad 12 is an angle presser plate 23 having the under side thereof provided with a strip of felt 24. The presser plate is suspended by coiled springs 25 from outwardly extending arms 26, carried by the walls 6. The top of the presser plate 23 is provided with finger pieces 27 whereby said plate can be easily lowered to press the flap of an envelop in engagement with the pad 12.

When the device is not in use, a triangular-shaped cover plate 28 can be placed upon the platform 5 to close the recess 11, and prevent evaporation. The plate 28 can be held in place by push pins 29, carried by the wall 2, these pins being pushed inwardly to engage in the end of the cover plate 28.

Arranged in the lower front edges of the end walls 2 is a transverse rod 30 and pivotally mounted upon said rod are the apertured ears 31 of a triangular-shaped presser head 32, said head having the underneath side thereof provided with a piece of felt 33. The head is normally retained in an elevated inclined position by coiled retractile springs 34 arranged adjacent to the ends of

the presser head, said springs having the upper ends thereof connected to the wall 4, as at 35 and the lower ends thereof to the edges of the head 32, as at 36.

5 In operation, the flap of the envelope is first opened and placed upon the pad 12 with the gummed and adhesively coated side thereof facing the pad. The presser plate 23 is then lowered to force the flap of 10 the envelope into engagement with the pad 12 and slightly compress said pad whereby the gummed flap will be moistened. The presser plate 23 is then released, the flap of 15 the envelope withdrawn and placed upon the base plate 1, beneath the presser head 32. This head is then lowered to close the flap and seal the envelope.

The device in its entirety can be made of light and durable metal, of various sizes 20 and is susceptible to any desired ornamentation.

While in the drawing there is illustrated a preferred embodiment of the invention, it is to be understood that the structural 25 elements thereof are susceptible to such

changes as fall within the scope of the appended claim.

What I claim is:—

A device of the type described comprising a platform, a reservoir supported thereby, a top plate closing said reservoir, an angle pad arranged in said platform, the walls of said reservoir having ports formed therein for conveying the contents of said reservoir to said pad, guides integral with 30 the reservoir walls and communicating with said openings, a spring supported presser plate arranged above said pad, and spring controlled valve stems extending through said top plate and having angle-shaped 35 lower ends projecting in said guides for controlling the outlet of the contents of said reservoir.

In testimony whereof I affix my signature in the presence of two witnesses.

JAMES HAMMOND.
